ATTORNEY

UNITED STATES PATENT OFFICE.

THEODORE E. CHARLBERG, OF MOLINE, ILLINOIS

SCREEN-FASTENER.

1,270,117.

Specification of Letters Patent. Patented June 18, 1918.

Application filed August 10, 1917. Serial No. 185,571.

To all whom it may concern:

Be it known that I, THEODORE E. CHARLBERG, a citizen of the United States, residing at Moline, in the county of Rock Island and State of Illinois, have invented new and useful Improvements in Screen-Fasteners, of which the following is a specification.

This invention relates to screen fasteners and one of the objects is to provide a device which may readily be attached to the side portions of the frame of a screen of usual construction, for the purpose of permitting the screen to be secured outside of a window sash, and without the necessity of using a ladder if the window to be screened happens to be in an upper story, and without the necessity of operating from the outside of any window when placing the screen in position and securing the latter.

20 A further object is to provide a device comprising a sheet metal blank suitably cut and bent into shape in order to provide for a main portion to be attached to the frame of the screen and a flanged portion having 25 an engaging slot and adapted to pass over the shank portion of a screw or the like previously placed in position in the window frame.

With the foregoing and other objects in view, the invention consists in the novel construction hereinafter described and claimed.

In the drawings:—

Figure 1 is a view of a full length screen in elevation showing my attachment applied thereto.

Fig. 2 is a further view in elevation showing the attachment applied to the central portion of a smaller screen.

Fig. 3 is a view in vertical section through a screen mounted in position in the window frame, and showing also the upper and lower sash.

Fig. 4 is a perspective view of the attachment.

45 Fig. 5 is a view of the blank of sheet metal from which the fastening device is formed.

In carrying out my invention I provide a blank of sheet metal comprising a main portion 10 and a wing portion 12 extending laterally from one edge thereof at about the

central portion of the main blank, said central portion being slotted longitudinally and shown at 15 for the purpose of permitting screws or other engaging devices to 55 pass through the slot when securing the fastener to the side of the frame of a screen.

Portion 14, constituting the engaging member designed to be brought into contact with a screw, pin, or other device connected 60 with the frame of the window, is bent along a line indicated by 16, said portion 14 being then deflected at substantially right angles to member 10.

The upper end of member 10 may be 65 curved or deflected with reference to the main portion of the device, this curved portion being designated 17, and the edge 18 thereof being brought into position adjacent to one edge of member 14, thus providing 70 a cover portion acting as a protecting member and preventing injury to the hands in manipulating the screen or window sash and also affording means for manipulation.

The screws passing through the slot 15 75 are designated 20, and two or more screws may be employed in suitable positions, the slot providing for adjustment as desired, after the screws have been inserted but not fully driven in, so that their heads will contact with the surface of plates 10.

The fasteners constructed as described are applied to the side members 24 and 25 of the frame of a window screen, and these fasteners are made in pairs in order that 85 the members 14 may be properly positioned with reference to the adjacent edge of the screen. These members 14 are similarly formed in each instance but are merely located on opposite sides of the plate portion 90 10. The slots of members 14 are designated 14'.

It is obvious that the device may also be employed for the purpose of securing an extra or storm sash to the outer portion of 95 a window frame, and that it may also be used for similar purposes in connecting adjacent elements which it is not desired to secure permanently.

I claim:—

The combination with a frame of a screen and the vertical side members thereof, of a

plurality of plate members secured to opposite sides of the frame on the inner surface thereof, said plate members being each provided with a flanged member having a slot 5 extending from the interior portion thereof to the outer edge, means carried by the frame of a window for engaging said slots

and a curved member extending from the end of the plate member and deflected from the main surface thereof over the flanged 10 portion to a point adjacent to the exposed edge and the upper free corner thereof.

In testimony whereof I affix my signature.
THEODORE E. CHARLBERG.
